UNITED STATES PATENT OFFICE.

JOHN G. BLESSING, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC CALLING DEVICE.

Application filed February 2, 1921. Serial No. 441,938.

To all whom it may concern:

Be it known that I, JOHN G. BLESSING, a citizen of the United States of America, and a resident of Chicago, Cook County, and State of Illinois, have invented certain new and useful Improvements in Automatic Calling Devices, of which the following is a specification.

My invention relates in general to automatic calling devices and more specifically to an improved type of impulse sending mechanism for use in transmitting calling impulses to control the operation of an automatic switch of any well known two wire type.

Among the features of my invention are to provide a simply constructed and simply operating device of the character described which is easy to manufacture and operate when installed.

Among the further features is to provide a simple method of prolonging the interval of time between the transmission of the final impulse of one digit and the transmission of the first impulse of the succeeding digit. It is well known that such a calling device is used in practice to first send one series of impulses to cause the vertical motion of the standard two wire Strowger selector, and the switch then operates automatically to select an idle trunk in the group elected. Therefore sufficient time must be given to permit this automatic trunk selecting function before the next series of impulses are transmitted. In order to accomplish the above result the finger dial is made larger than usual, and has a longer space between the No. 1 finger hole and the finger stop. It will be understood that were no special means provided to prevent it, this dial when operated by the first finger hole would move its cam a sufficient distance to send two impulses or one extra impulse for each series dialled. Means are provided as will be explained for preventing the transmission of this extra impulse by moving the cam out of the path of the impulse springs at a critical time. Other features of improvement will be explained in the following detailed description of the accompanying drawings in which:

Fig. 1 is a front view of the device with the plate 2 (Fig. 2) removed.

Fig. 2 shows the plate 2 covering the front of the dial.

Fig. 3 is a top view of the device showing the impulse and shunt springs and their relation to the impulse cam or interrupter.

Fig. 4 is a rear view of the device showing the governor and related devices.

Fig. 5 is a front view of the device with the finger dial and number plate removed showing the operating gears.

Fig. 6 is a rear view of the finger hole dial showing the gear and ratchet devices mounted on the rear thereof, the gear being partly cut away to show the ratchet.

Fig. 7 is a side view of the governor.

Figs. 8 and 9 are detailed views of the interrupter cam and its unit assembly showing how the cam and gear are operated to eliminate the final impulse to prolong the time interval between any two successive series of impulses.

I will now describe the features and method of operation of this calling device more in detail.

This calling device comprises the usual finger hole dial 1 mounted on a plate 3. This plate 3 is a casting formed from any light and durable material and is so simply designed that it requires no machine operations except the threading of certain holes. The various mounting lugs are formed in the casting and thus the device is very simple of construction and has very few detachable parts.

The finger dial 1 is mounted by means of a screw 4 to the plate 3 and carries a power spring 5 one end of which is attached to a lug on the side of screw 4 and the other end of which is fastened to one of the lugs 6 turned up from the dial 1. The dial 1 has a longer space between the number 1 finger hole and the finger stop than is usual in such dials, this space being so proportioned that the dial by means of its gears always rotates the impulse cam one extra revolution for each digit, which last revolution is however, rendered ineffective as will be explained. A combined pawl and stop 7 is pivoted at 8 on the dial and has two teeth 9 and 10 cooperating with the ratchet wheel 14. An arm 11 of this ratchet 7 extends towards the circumference of the dial and lies in the path of a stop pin 12 projecting inward from the finger stop so that when the dial is returned to normal, after operation, the arm 11 first meets the pin 12 and is rotated about its pivot a slight distance.

to meet the stop pin 13 in the dial. This movement of the arm 11 is just sufficient to cause pawl 10 to disengage from the teeth of ratchet wheel 14 and cause pawl 9 to engage said teeth to thus positively stop the dial and the ratchet. The spring 12' normally tends to hold the pawl 10 in engagement with the ratchet teeth 14 and the arm 11 away from the stop pin 13. As the dial 10 is rotated forward the pawl 10 rides over the teeth 14 and upon the return movement of the dial the pawl 10 engages said teeth to cause ratchet 14 to be rotated backward with the dial.

15. The cover plate 2 (Fig. 2) is slotted and fits over the front of the finger dial to cover all parts thereon and is held in place by a screw 15.

On the back of the plate 3 are mounted 20 the interrupter springs 16 and 17 and the shunt springs 18 and 19. The springs 16 and 17 are opened in the operation of the device by the cam 20 to send impulses and the springs 18 and 19 are closed as the dial 25 moves off normal to shunt the talking equipment at the telephone during impulses.

In Fig. 4 is shown the governor comprising a spring 21 having a curved arm at each end thereof carrying weights 22 having friction material on the outer edge thereof which rubs against the inner wall of the cup 23 when the governor revolves. This governor is attached to a hub which is loosely mounted on its shaft and revolves freely in 30 one direction. The pawl spring 24 is attached to the governor and cooperates with the teeth of a ratchet wheel 25 so that when the gears revolve the governor is carried with them but when the gears come to a 35 positive stop said governor may rotate on freely until it comes to a stop of its own accord, thus preventing any strain on the governor.

In Fig. 5 are shown the gears by which 40 the movement of the dial is communicated to the cam 20.

The cam 20 and the gear 26 are mounted 45 on opposite ends of an endwise movable shaft 27, the spring 19 normally tending 50 to force the shaft 27 inward. On the under side of the dial is mounted a rounded lug 28, (Figures 3, 8 and 9) which rides over the rounded surface of the gear 26 as the dial rotates through the final portion of its movement 55 just before reaching normal, thus forcing the shaft outward against the tension of spring 19 to move the cam outward and prevent its engagement with the springs 16 and 17 and also to open the springs 18 and 19. 60 Thus it will be seen that even though the cam has one extra revolution, this last revolution does not send an impulse by opening springs 16 and 17. Cooperating with the teeth of gear 26 is a loosely mounted gear 65 and pinion 29 the pinion teeth of which en-

gage with the gear 30 which is also a part of a combined gear and ratchet and which is loosely mounted on a sleeve 31 on the dial 1. The sleeve 31 fits over the threaded stud 70 32 and the mechanism is all held in place by screw 4 (Fig. 1). The gear 33 of the governor also meshes with the teeth of the gear 29 underneath the piece 34 which is held to the plate 3 by screws and forms a pivot point for the gear and pinion 29 by 75 means of armature 35.

Thus the dial when rotated forward stores tension in spring 5 and ratchet 10 rides over wheel 14 without moving said wheel. The amount of force required to operate the wheel 14 must be sufficient to also operate the entire connected gear train and the tension of the spring 12' being very slight is usually not sufficient to do this; however, if the wheel 14 should happen to start to turn, the back of the cam 20 will engage the back of the impulse springs and prevent further movement of the wheel. As the dial returns the wheel 14 is rotated with the dial by ratchet 10 carrying also 90 gear 30. The movement is communicated through gear 30, pinion on gear 29, gear 29, gear 26 to the cam 20 thus interrupting springs 16 and 17 a number of times. The movement is governed by the action of the 95 governor, the parts 22 being thrown out by centrifugal force and rubbing on the wall 23 to retard movement.

As the dial nears normal position lug 28 rides upon gear 26 and moves the cam 20 100 outward so that the last revolution of the cam does not operate the springs 16 and 17.

The shunt springs 18 and 19 are opened by this movement of cam 20 thus insuring that the last impulse has been transmitted. 105

It will thus be seen that I have provided a very efficient and simply constructed type of calling device which delays the transmission of the first digit of any impulse a certain length of time after the transmission of the last impulse of a preceding digit and which has other features and details of improvement which will be pointed out in the appended claims. 110

What I claim as my invention is:

115

1. In a calling device, springs, a shaft carrying a gear on one end and a cam interrupter on the other end, said shaft movable endwise, a rotatable finger hole dial, a projection on said dial directly engaging 120 said gear, said projection moving said gear shaft endwise while the cam is rotating to operate said springs.

2. In a calling device, a rotatable finger hole dial, a ratchet wheel mounted adjacent 125 thereto, a double ended pawl mounted on said dial, means rendered operative upon movement of the dial in one direction for causing one end of said pawl to engage said ratchet wheel and means effective at another 130

time to cause the other end of the pawl to engage said ratchet wheel.

3. In a calling device, a rotatable finger hole dial, a ratchet wheel mounted adjacent thereto, a double ended pawl mounted on said dial, one end thereof normally engaging the teeth of said ratchet wheel so that the wheel is carried with the dial when rotated in one direction, and means for causing the other end of said pawl to engage the teeth of said ratchet wheel to stop the wheel.

4. In a calling device, a rotatable finger hole dial, a ratchet wheel mounted adjacent said dial, a combined pawl and stop mounted on said dial, said pawl having one arm co-operating with the teeth of said ratchet to drive the ratchet, another arm co-operating with the teeth of the ratchet wheel to stop the operation of the wheel, another arm and means for operating it to render said second arm effective.

5. In a calling device, a rotatable finger hole dial, a movable member carried by said dial, a finger stop having an auxiliary stop, a spring attached to said dial normally tending to rotate the same, and a fixed member on the dial for preventing the rotation of said dial by its engagement with said movable member, and by a resultant engagement of said movable member with said auxiliary stop.

6. In a calling device, a rotatable finger hole dial, a toothed wheel, a finger stop provided with an auxiliary stop, a movable member carried by said dial and having a plurality of arms, one of said arms normally engaging said wheel to prevent its rotation in one direction while another of said arms engages said auxiliary stop to prevent the rotation of said dial, and means including a spring attached to said dial for maintaining said arms in the afore mentioned position.

7. In a calling device, a rotatable finger hole dial, a toothed wheel, a finger stop provided with an auxiliary stop, a movable member carried by said dial and having a plurality of arms, one of said arms normally engaging said wheel to prevent its rotation in one direction while another of said arms engages said auxiliary stop to prevent the rotation of said dials, means

including a spring attached to said dial for maintaining said arms in the afore mentioned position, and means on said dial released when the dial is rotated for moving said member to an alternate position to cause another arm to engage said wheel to cause the same to be rotated by power stored in said spring when the dial is released.

55

8. In a calling device, springs lying in one plane, a shaft having spring operating mechanism fixed to one end thereof and a wheel on the other end thereof, a rotatable finger hole dial having a cam mounted thereon, said cam normally engaging said wheel to hold the operating mechanism associated with said shaft in another plane, means for moving said operating mechanism into the plane in which said springs are lying when the dial is rotated in one direction, and a gear train for rotating said operating mechanism to operate said springs when the dial is rotated in the reverse direction.

75

9. In a calling device, impulse sending mechanisms, driving mechanisms therefor, a finger hole dial, a spring wound up by the forward movement of the dial, which returns the dial to normal, a combined pawl and stop associated with the dial and controlled by the return thereof to operate said mechanisms, said pawl and stop operated when the dial reaches a predetermined position to stop both the dial and the mechanisms.

80

10. In a calling device of the rotatable dial type, a stop fixed to the frame, a lever pivoted on the dial and adapted to engage said stop during the return of the dial to normal, and a second stop fixed to the dial and adapted to engage said lever after the same has engaged said first stop.

90

11. In a calling device comprising a rotatable dial and a sending mechanism, a gear train for operating the sending mechanism when the dial returns to normal, a stop fixed to the frame, and a lever pivoted to the dial and operated by said stop when the dial reaches normal position to stop said gear train.

95

Signed by me at Chicago, Illinois, this 13th day of January, 1921.

JOHN G. BLESSING.
